WRAPPING MACHINE

Joseph Hexter and William E. Lanham, Atlanta,
Ga., assignors to Columbia Baking Company,
Atlanta, Ga., a corporation of Delaware

Application January 13, 1941, Serial No. 374,146

7 Claims. (Cl. 93—2)

This invention relates generally to wrapping machinery and specifically to improvements in such machines to enable them to wrap and seal twin packages.

An object of this invention is to simultaneously convey a pair of half-loaves or other articles through suitable duplex mechanisms for enveloping said half-loaves in individual wrappers and enclosing the ends thereof for heat sealing and delivery in pairs. An incidental object is to make the operation or functioning of the mechanism automatic so as to require no attention from the operator beyond seeing that the apparatus is kept supplied with wrapping material and articles to be wrapped.

Another object of this invention is to produce a "two-in-one" package by enclosing the aforementioned pairs of wrapped packages within a common outer wrapper and enfolding the ends for heat sealing.

A further object of this invention is to provide two pairs of movable tucker blades on the elevator table and to feed in unison one of a pair of webs between each pair of tucker blades and to tuck in the ends of the wrappers partly enfolded around the articles during transfer from the conveyor to the elevator table. Also cooperating with each pair of tucker blades are back tension plates yieldingly mounted to compensate independently of each other for variations in widths of the pairs of articles transferred to the elevator table. Two pairs of retaining fingers also function to engage the front of the half-loaves and hold them securely in position as the elevator table rises to its horizontal station.

A further object is to provide guide-ways so constructed as to permit adjustment in width to accommodate pairs of articles varying in that dimension.

A further object is to provide novel construction of the compound pushers for simultaneously transferring successive pairs of articles from the transverse conveyor to the elevator table.

A still further object is to provide heat sealing means and cooling means for rapidly and efficiently binding together all folded ends of the wrappers on the half-loaves.

Referring now to the accompanying drawings:

Fig. 1 is a plan view diagram disclosing the sequence of operations performed upon the loaves to be wrapped.

Fig. 2 consists of a series of isometric views showing the various stages through which the loaves progress.

Fig. 3 is a side elevation of the machine em-

bodying a slicer, half-loaf separator, and half-loaf wrapping machine.

Fig. 4 is a side elevation along lines 4—4 of Figs. 5 and 6, showing the half-loaf wrapping machine partly broken away to reveal certain mechanisms and the hot and cold sealing units leading to the final outer wrapping machine which is only partially illustrated.

Fig. 5 is a plan view of Fig. 3.

10 Fig. 6 is a plan view of Fig. 4 showing only the cold sealing units and the conveyor therefrom to the final outer wrapping machine, which is only partially illustrated.

Fig. 7 is a transverse vertical section on lines 15 7—7 of Fig. 6.

Fig. 8 is a transverse vertical section on lines 8—8 of Fig. 5.

Fig. 9 is an enlarged plan section on lines 9—9 of Fig. 4 illustrating the tucking and folding 20 blades and the hot sealing means.

Fig. 10 is a transverse vertical section on lines 10—10 of Fig. 9.

Referring now to Fig. 1 and Fig. 2, the sequence of operations upon the loaf will be described.

25 The unsliced loaf A is placed upon conveyor 10 and passes through the machine 12 to emerge either as two half-loaves or as a sliced loaf B, depending upon the construction of the machine 12, to be carried away on conveyor 14 and sepa-

30 rated by laterally diverging guide-ways into two half-loaves, preferably sliced as shown at C. These are then transferred in pairs to transverse conveyor 16 and delivered to the duplex wrapping machine 18 where the half-loaves are individ-

35 ually wrapped in waxed paper or other suitable material as shown at D. Conveyor 20 moves the wrapped half-loaves D between laterally converging guide-ways thus uniting the wrapped half-loaves, as shown at E, prior to passing onto trans-

40 verse conveyor 22 for delivery to wrapping machine 24 where a pair of individually wrapped half-loaves are enclosed in a common outer wrapper, as shown at F, and delivered therefrom by conveyor 26.

45 The apparatus for carrying out the operations just described, produces a "two-in-one" package that has been effectively wrapped and at a high productive rate per unit of time.

The embodiment of the invention illustrated in 50 the accompanying drawings is one form the apparatus would take for wrapping sliced half-loaves of bread. Referring now particularly to Figs. 3, 5 and 8, the conveyor 10 carries the loaf to a slicing machine 12 of the desired construction arranged or adjusted to produce slices of

55

the desired thickness. As the sliced loaf emerges from the slicing machine, it is deposited and transported in spaced relationship to succeeding half-loaves upon a continuously driven conveyor 14 consisting of endless parallel chains 28 connected by uniformly spaced bar flights 30 travelling over conveyor table-top 32 supported by frame 34. Suspended above the conveyor flights 30 are two pairs of diverging guide-ways 36 and 38 uniting to form a central partition or blade 40 at the slicer 12 to function as a separator to divide the sliced loaf into two halves, the diverging guides 36, 38 effecting a further separation of the two half-loaves for delivery to a transverse conveyor 16. The guide-ways 36, 38 are conveniently suspended from frames 42 and mounted in such manner as to be adjustable horizontally by means of wing-bolts 44 (Fig. 8) to align the blade 40 with a cut through the loaf.

The pair of separated half-loaves are now transferred to spaced flights 46, 48 of transverse conveyor 16 which intermittently carries them in spaced relationship to the duplex wrapping machine 18. Pusher arms 50 carried by shaft 52 are oscillated in unison through linkage 54 actuated by suitable mechanism not shown. The movement of arms 50 is so timed that they deliver a pair of half-loaves simultaneously to conveyor 16 as flights 46 and 48 are at rest ready to receive the half-loaves. Conveyor 16 consists of two driven parallel chains 56 and 58 which are adjustable in their longitudinal relationship, and since the flights 46 are carried by one chain and the flights 48 by the other chain, it is possible to adjust the distance between the pairs of flights 46, 48 to accommodate various lengths of half-loaves or other articles.

The pair of half-loaves carried by transverse conveyor 16 come to rest at a transfer station within duplex wrapping machine 18 as illustrated on Fig. 4. At this point, in alignment with the pair of spaced half-loaves, is a pair of pusher plates 60 carried by a pair of parallel plungers 62 mounted in brackets 64 and connected for simultaneous reciprocation by cross-head 66 to linkage 68 and rock shaft 69 actuated by a suitable cam (not shown). The pusher plates 60 pass between flights 46, 48 to transfer the pair of half-loaves onto elevator table 70 which is swung around its supporting shaft 72 to a horizontal position by link 74 operated by a suitable cam (not shown).

Brackets 76 support a pair of rolls 78 of waxed paper or other desirable wrapping material to provide two parallel webs of paper 80—one for each half-loaf wrapping position. The web-feeds, not illustrated in detail, may be of any suitable type, for example the one disclosed in Patent No. 1,626,409, issued April 26, 1927, to G. W. Gwinn.

The webs 80 are guided through suitable rollers to a position where their loose ends are disposed at the transfer station between the side of the transverse conveyor 16 and the edge of elevator table 70 as shown in Fig. 4. As the half-loaves are transferred onto the elevator table 70, they engage the depending portions 82 of the webs 80 and draw them along, thus causing the webs to become partly wrapped around the half-loaves as they are pushed against back tension plates 84, Figs. 9 and 10, slidably mounted on elevator table 70 to facilitate the enfolding of the half-loaves within the webs. Also during this transfer operation, the wrapping material extending beyond the ends of the half-loaves is

tucked in by four movable tucker blades 86, 88, 90 and 92. These tucker blades are attached to arms 94, 96, 98 and 100 respectively, which in turn are adjustably secured in pairs to slideable brackets 5 on shaft 72 at either side of the pivoting boss of elevator table 70. Arms 94 and 98 are attached to bracket 102, and arms 96 and 100 are attached to bracket 104. Attached to brackets 102 and 104 respectively, are plate cams 106 engaging rollers 108 carried by loose hub 110 on shaft 72, said hub being intermittently rocked by suitable cam, not shown, through linkage 112. Plate cams 106 and 107 are urged against rollers 108 by springs, not shown, acting against the brackets 104 and 102. 15 When the elevator table 70 is in its lower position to receive the half-loaves, the rollers 108 will have been rocked to the left, as viewed in Fig. 9, forcing the plate cams 106 apart, thus spreading tuckers 86, 88 and 90, 92 to enable the half-loaves to enter between them. As the half-loaves enter the rollers 108 resume their former position, shown in Fig. 9, and the tucker blades move against the ends of the half-loaves to tuck in the wrapping material.

20 As the elevator table 70 swings upwardly towards its horizontal position, two pairs of fingers 114 (Figs. 4, 9 and 10), operated by suitable connections (not shown), to the driving mechanism are moved upward into position to retain the half-loaves on the elevator table 70 and against the back tension plates 84. When table 70 has reached its horizontal position, its surface is then in the same plane as the sealing table 116 to which the partially wrapped half-loaves are to be transferred.

25 During the ascent of the elevator table 70 with the partially wrapped half-loaves, additional wrapping material is drawn off the rolls 78 and the webs are draped over the back sides 40 of the half-loaves by cam controlled rollers, not shown. Referring to Fig. 4, feed rollers 118, which are mounted in pivoting frame 120 operated by connecting link 122 from suitable mechanism as disclosed in Patent No. 2,118,513 issued May 24, 1938, to T. Jensen, are pressed against similar rollers, not shown, carried in the edge of the elevator table 70; thus holding the webs of wrapping material between them. the feed rolls 118 can be controlled in such manner as to rotate and feed any desired additional amount of wrapping material, or the rolls can be rotationally reversed to exert tension on the webs, or they may rotate idly. Prior to advancing the half-loaves onto the sealing table 116, 50 a knife 124, carried on a pivoting frame 126 actuated through link 128 by a suitable cam, not shown, functions to effect the severance of the two webs of wrapping material.

55 Also during the ascent of the elevator table 70, the partially enfolded half-loaves pass between pairs of yieldingly supported top folders 130 and 132 which engage the wrapping material extending over the top edges of the half-loaves and fold it down over the tucker blades, 86, 88, 90 and 92. The half-loaves are now in position to be moved horizontally across the sealing table by means of paired pusher arms 134 of a well known type carried by rods 136 connecting parallel continuously driven sprocket chains 138. As the half-loaves are engaged by pusher arms 134, the retaining fingers 114 are automatically withdrawn, permitting the half-loaves to pass between pairs of plough folders 140, 142 (Figs. 4 and 9) and to slip the partly folded wrappers off of the tucker blades 86, 88, 90 and 92. Thus

the wrapper flaps extending laterally at the leading sides of the half-loaves and between the adjacent vertical edges of folders 130, 140 and 132, 142 will be folded against the ends of the half-loaves. The half-loaves next pass between the pairs of bottom folders 144 and 146, and the laterally extending wrapper flaps at the bottoms of the half-loaves pass into upwardly inclined slots 148 (Fig. 4) formed between adjacent edges of folders 140, 144 and 142, 146, and are folded against the ends of the half-loaves as the final folding operation. The fully enfolded half-loaves then continue to pairs of heated end sealers 148, 150 (Figs. 5 and 9) and over heated bottom sealers 152, 154 which cause the folded overlying flaps to adhere to one another to produce a sealed wrapper.

The inner adjacent folders are carried by a common bar 156 suspended from cross-bars 158, 160, and the outer folders are mounted on arms 162 and 164. The heated sealers 148 and 150 are supported in any suitable manner and along with the folders, provision is made for lateral adjustment to permit passage of articles of lesser or greater lengths.

As the fully wrapped and sealed half-loaves are pushed into the seal cooling unit, the pusher arms 134 are withdrawn and the half-loaves are then engaged by conveyor bar flights 166 carried between parallel driven sprocket chains 168 over conveyor table 170, Fig. 6. Suspended over the conveyor table 170 are two pairs of refrigerated hollow guide-ways 172 and 174 to effect rapid cooling of the sealed wrapper ends. The inner adjacent guides are carried by frame members 176 and 178, while the outer guides are mounted on brackets 180 (Fig. 4) which in turn are carried by side-rails 182. Brackets 184 support the side-rails 182 and are mounted on threaded shafts 186 to permit lateral adjustment of the outer guides 172, 174 to accommodate articles of various lengths. Connections 188, through which the refrigerant is circulated and through the hollow guides 172, 174 are made of flexible material to permit lateral adjustment of the guides. For the purpose of cooling the bottom seals of the half-loaves, a refrigerated hollow member 190 with inlet 192 and outlet 194 is fastened underneath conveyor table 170 at the entering end.

As the half-loaves emerge from between the refrigerated guides 172, 174, they enter between converging guide-ways 196 carried by brackets 198 which are supported by side-rails 182. During the passage of the half-loaves between the guide-ways 196, they are brought together at their inner adjacent ends as shown at E, Fig. 2, and then as a unit are transferred by oscillating arms 200 to transverse conveyor 22, which is similar to conveyor 16 except that the flights 202 are smaller and are spaced further apart so as to receive two half-loaves as a unit. The united wrapped half-loaves are then carried to the final wrapping machine 24, where they receive the outer wrapper to form the "two-in-one" loaf package.

The wrapping material used in machine 24 consists of a single web of sufficient width to cover the united half-loaves and allow enough for the end folds. The operations and mechanism required for folding and sealing are identical with those for the outer ends of the half-loaves in the duplex wrapping machine 18, with the exceptions that wrapping machine 24 does

not utilize inner tuckers 88, 90, the inner folders, and the inner hot and cold sealers.

The fully wrapped and sealed loaves emerge from wrapping machine 24 upon conveyor 26 as a finished "two-in-one" package.

In the foregoing the invention has been explained as applied to a bread wrapping machine constructed to wrap separately the two halves of a loaf of bread and then enclose the same two halves in an outside wrapping; but it is apparent that the invention is not limited to such bread wrapping or to the preliminary wrapping of only two units. It can be employed, with suitable modifications and changes, obvious to those skilled in the art, in machines for preliminarily wrapping a single article or any number of units or articles and then enclosing any desired multiple of the wrapped articles in an outside wrapping. Also, instead of bread wrapping machines, the invention is obviously capable of embodiment in machines for wrapping other articles such as, for example, cakes, cigarettes and chewing gum. The invention is, therefore, not to be construed as limited either as to construction or as to purpose except to the extent stated in the claims which follow.

What is claimed is:

1. A wrapping machine comprising a lifter table movable from a lower article receiving position to an upper article delivering position, two pairs of tuckers on said table, mechanism for moving apart the tuckers of both pairs to receive articles and then returning them into engagement with the articles, devices for guiding a pair of wrappers into positions in front of the table and the tuckers, and means for pushing a pair of articles on the table and between the tuckers while the tuckers are separated whereby each of the articles will be simultaneously partially enfolded in one of the wrappers and the ends of the wrappers tucked over the ends of the articles, the return of the tuckers to unseparated position pressing the tucked wrappers against the articles.
2. In a wrapping machine, an intermittently moved carrier, a pair of carriers for delivering two halves of a loaf in spaced apart relation to the intermittently moved carrier, a transfer table for receiving the loaf halves and raising them into alignment with separate wrapping mechanisms, a pair of tuckers on said table for each half loaf, devices for moving both tuckers of each pair apart to receive the half loaves and then returning them to original position, a pusher for pushing each half loaf to the transfer table and between the tuckers while the tuckers are separated, means for holding a web of wrapper material in the path of each half loaf as it is pushed on the table and between the tuckers and partially enclosing the half loaves and folding ends of the wrapper, return of the tuckers to original position pressing the folded ends of the wrappers against the half loaves, and means for thereafter completing the end folding and sealing of the wrappers.
3. In a wrapping machine, the combination with means for advancing a pair of articles to a predetermined station, of a lifter table movable from a lower position to an upper position, two pairs of tuckers on said lifter table, mechanism for spreading the tuckers of each pair apart to receive articles and then returning them to their original positions, means for transferring a pair of articles from the aforesaid

predetermined station to the lifter table while the tuckers are spread apart, and means for guiding a pair of wrappers across the paths of the articles being transferred to the lifter table whereby each of said articles will be partially enfolded in one of said wrappers and the ends of the wrappers tucked in by the tuckers during said transfer.

4. In a wrapping machine, the combination with means for advancing a pair of articles to a predetermined station, of a lifter table movable from a lower position to an upper position, two sets of tuckers on said lifter table, means for simultaneously delivering a pair of articles side by side from said station to said lifter table at the lower position thereof, devices for guiding a pair of wrappers across the path of articles being delivered to said table whereby each of said articles will be partially enfolded in one of said wrappers during delivery to said lifter table and the ends of the wrapper will be tucked over the ends of the articles by the tuckers, and means for actuating the tuckers to press the wrappers against the ends of the articles.

5. An apparatus for separately wrapping the halves of a loaf and then reuniting the halves in a sealed outside wrapper comprising a pivoted elevator table, a pair of blocks pivoted on and shiftable laterally on the same pivot as the elevator table, a pair of tuckers having the tuckers of each pair attached to a different one of said blocks, means for moving said blocks apart and then returning them to original position whereby to spread the tuckers apart and then return them to original position, means for holding a web of wrapping material across the free ends of each pair of tuckers, and means for inserting the half loaves between the tuckers while the tuckers are spread apart, whereby to cause the tuckers to partly enfold the half loaves in said webs, and means for thereafter completing the folding and sealing of the respective wrappers.

6. An apparatus of the character described, comprising a bread slicing machine, guides con-

structed to divide the sliced loaf into halves and guiding the halves apart to a spaced relation with the two halves maintained in axial alignment as the sliced loaf is carried into and through the guides, carrier mechanism for transporting the sliced loaf into and through said guides, a pair of wrapping machines for simultaneously and separately wrapping the two halves of the loaf, means for simultaneously progressing the two halves of the loaf through said two wrapping machines constructed to maintain the two halves in substantially the spaced apart and axially aligned relation determined by the aforesaid guides until the wrapping is completed by the wrapping machines, means for moving the two wrapped halves endwise into juxtaposition, a final wrapping machine for enclosing the juxtaposed halves in an outside wrapper, and a carrier mechanism for delivering the juxtaposed halves to and removing the wrapped unit from said final wrapping machine.

7. An apparatus of the character described, comprising a bread slicing machine, guides constructed to divide the sliced loaf into halves and move the halves apart and in axially aligned relation when the loaf is carried into and through said guides, a carrier for carrying the sliced loaf from the slicing machine into and through said guides, a pair of wrapping mechanisms for simultaneously wrapping the sliced halves of the loaf in separate wrappers, devices for progressing the halves sidewise to and through said wrapping mechanisms constructed to maintain the two halves of the same loaf in axial alignment and spaced apart substantially to the extent determined by the aforesaid guides, devices for moving the halves of the loaf together after the separate wrapping is completed, a final wrapping machine for enclosing the separately wrapped halves in an outside wrapper, and means for delivering the two wrapped halves as a unit to the final wrapping machine.
